UNITED STATES PATENT OFFICE.

WILLIAM E. KIMMELL, OF SEYMORE, INDIANA, ASSIGNOR TO THE ANTI-SEPTIC PEAR COMPANY, OF SAME PLACE.

DESIGN FOR A SUPPOSITORY-TABLET.

SPECIFICATION forming part of Design No. 32,718, dated May 29, 1900.

Application filed May 3, 1900. Serial No. 15,419. Term of patent 14 years.

To all whom it may concern:

Be it known that I, WILLIAM E. KIMMELL, a citizen of the United States, residing at Seymour, in the county of Jackson and State of Indiana, have invented a new and original Design for Suppository-Tablets, of which the following is a specification.

My invention relates to a new and original design for suppository-tablets and is shown in the accompanying drawings, in which—

Figure 1 is a top plan view; Fig. 2, a side perspective view; Fig. 3, a bottom plan view, and Fig. 4 is a central longitudinal section. The leading features of my design reside in a suppository-tablet which is narrow at its head end and widens out with diverging ogee sides to a broad butt-end, the upper surface of which presents an ogee curve convex at the narrow end, concave at the neck adjoining the head end, and then convex at the broad butt-end, the bottom surface of which is convex throughout and the circumferential edge of which between the top and bottom surfaces is flattened.

In the accompanying drawings the refer-

ence-numeral 1 indicates the suppository-tablet, which has a narrow head end 2 and the sides of which diverge on ogee lines to a broad butt-end 3. The top surface of the tablet presents an ogee curve convex at the head, 30 as shown at 4, curved at the neck 5, and convex at the butt-end, as shown at 6. The bottom surface 7 is convex throughout, as shown.

The numeral 8 indicates the flattened circumferential edge between the top and bottom surfaces. 35

My design is embodied in a suppository-tablet of novel and distinguished appearance.

Having thus described my invention, what I claim is—

The design for a suppository-tablet herein shown and described. 40

In testimony whereof I have hereunto set my hand in presence of two subscribing witnesses.

WILLIAM E. KIMMELL.
